Victor J. Evans

ATTORNEY

UNITED STATES PATENT OFFICE.

JAMES E. KREILING, OF CHICAGO, ILLINOIS.

SORTING DEVICE.

Application filed January 31, 1927. Serial No. 164,924.

This invention relates to certain novel improvements in sorting devices and has for its principal object the provision of an improved construction of this character which will be highly efficient in use and economical in manufacture.

It is an object of the invention to provide a sorting device which will be light in structure and capable of expeditious use whereby 10 to sort printed material or the like and which may be placed upon the desk or table of the user without injuring the same.

A still further object of the invention is to provide a sorting device of the character 15 hereinafter set forth which comprises a plurality of separating leaves or sheets pivoted for movement in opposite directions upon themselves to provide what may be termed pockets for receiving the sorted matter and 20 it is intended that the unsecured end of each leaf or sheet be provided with a suitable holder for the insertion of an indicia-bearing card, thus enabling the user to number the sheets in numerical or alphabetical 25 order.

A still further object of the invention is the provision of a simple combination and arrangement of parts for pivotally connecting each of the leaves or sheets to a common 30 base board.

Other objects will appear hereinafter.

The invention consists in the novel combination and arrangement of parts to be hereinafter described and claimed.

35 The invention will be best understood by reference to the accompanying drawings, showing the preferred form of construction and in which:

Fig. 1 is a top plan view of an embodiment of the invention;

Fig. 2 is a side elevational view of the same;

Fig. 3 is a perspective view of one of the separating leaves or sheets embodying the 45 invention;

Fig. 4 is a fragmentary sectional detail view taken substantially on line 4-4 of Fig. 1;

Fig. 5 is a perspective view of a clip embodied in the invention; and

Fig. 6 is a perspective view of a fastening element embodied in the invention.

Referring to the drawing, showing the preferred form of construction, 10 indicates 55 a base board which in one instance is adapted to be mounted flatly upon the desk or

table of the user. To prevent the base board from scratching or otherwise damaging the surface upon which it is supported, there is provided at each corner of the base board 60 rubber feet 11, Fig. 2. These feet 11 are secured to the base board, which may be of any approved material, in any approved or well-known manner.

Secured to the base board and extending 65 longitudinally with respect thereto, is a strip 12 preferably formed of suitable metallic material. The end 13 of the strip 12 is disposed inwardly from the corresponding end 70 of the base board whereby to provide an uncovered surface of the base board for the reception of printed advertising or direction matter. This strip 12 is secured to the top surface of the base board 10 through the medium of screws 14. Formed in the strip 12 in a longitudinal direction with respect thereto, are two parallel rows of loops 15. These loops 15 in the present instance are struck from the body of the strip 12 to provide bearing sleeves for trunnions 16 formed 75 at the end portions of wire bails or clips 17. These bails 17 provide hinge connection between the strip 12 and the separating leaves or sheets 18 and the connection between the bail 17 and the leaf or sheet 18 is accomplished in the following manner.

Each clip 17 is associated with its respective sheet 18 by mounting the bight portion 19 of the clip within a folded metallic clip 20. This clip 20 is secured to its respective 80 sheet 18 by disposing its limb portions on opposite sides of the sheet and inserting a ring-like protuberance 22 through a hole 23 formed in the sheet. The ring-like protuberance 22 after being inserted through the hole 23 projects through an opening 24 formed in the opposite limb portion of the clip and the edge of the ring-like protuberance is spun or otherwise turned to provide a head for securely attaching the clip to its respective sheet. The bight portion 19 of each of the clips 17 has formed thereon a substantially 85 triangular projection 25 which is adapted to engage in a substantially triangular notch portion 26 formed in the sheet to which this clip is attached. This projection 25 functions to cooperate with the notch 26 to prevent lateral movement of the sheet to which it is attached, thereby holding the sheet in proper alignment with the next succeeding sheet of the sorting device.

The unsecured end portion of each sheet

has secured thereto a substantially U-shaped transparent holder 27 which is secured to the sheet through the medium of clips 28, Fig. 3. The upper inner edges of the holder 5 is covered through the medium of a suitable cloth or paper strip 29 which is adhesively secured to the same and to the sheet.

The holder 27 is adapted to receive a paper strip which has printed thereon a 10 number or letter of the alphabet whereby to index the sheets in numerical or alphabetical order. It is also pointed out that the paper strip received by the holder may have printed thereon other printed matter than a 15 number or alphabetical letter, this being optional to the user.

In use, the separating leaves, which provide pockets, are disposed upon each other and when in this position it will be apparent 20 that the unsecured end portions of the leaves are arranged in step formation whereby to expose the paper strip bearing the printed indicia thereon. The printed matter to be sorted is disposed in its proper 25 pocket provided by the separating leaves or sheets and by reason of the simplicity of connection between the leaves or sheets, it will be manifest that convenient access may be had to any one of the leaves for depositing 30 printed matter in the pockets thereof during sorting.

In use, the device is placed upon the surface of a desk or table and in such position slipping of the device during use is prevented 35 by reason of the rubber feet.

The leaves may be formed of any approved material such as cardboard or the like and if desired the leaves may be divided into sets of different lengths.

40 By reason of the projections 25 on the clips and their engagement in the notches 26, the leaves will be held in proper alignment with respect to each other and be also more rigidly connected to their clips. The 45 device when completed and when constructed in accordance with the description herein set forth will be light in structure, thereby facilitating expeditious moving about by the user.

50 By the novel manner of connecting the separating leaves or sheets to the strip it will be seen that the same can be easily removed when worn out or for substituting different sizes therefor. This is accomplished 55 by springing the trunnions from engagement with their respective bearing sleeves.

While I have illustrated and described the 60 preferred form of construction for carrying my invention into effect, this is capable of variation and modification, without departing from the spirit of the invention. I, therefore, do not wish to be limited to the 65 precise details of construction set forth, but desire to avail myself of such variations

and modifications as come within the scope of the appended claims.

Having thus described my invention what I claim as new and desire to protect by Letters Patent is:

70 1. In a sorting device, a base board, a plurality of separating members, and means for securing corresponding end portions of the separating members to the base board to permit turning movement in opposite directions upon themselves and to dispose the unsecured end portions of the members in step formation, said means including clips 75 pivotally connected to the base board and including bight portions having projections 80 formed thereon, and clip elements securing the bight portions to the separating members, said separating members having notches formed therein for the reception 85 of said projections.

90 2. In a sorting device, a base board, a strip secured to the base board and extending longitudinally with respect thereto, protuberances formed on said strip providing bearing sleeves, clips having end portions bent to provide trunnions for engagement in the bearing sleeves, a plurality of separating members adapted to be disposed in facial abutment with respect to each other, and clip members secured to corresponding 95 end portions of the separating members and bent to receive portions of the clips.

100 3. In a sorting device, a base member, a strip secured to the base member and having parallel rows of protuberances formed thereon providing bearing sleeves, clips formed substantially U-shaped and having end portions providing trunnions adapted to detachably engage in said sleeves, a plurality 105 of separating members, and clips secured to the separating members and bent to receive the bight portions of the first-mentioned clips whereby to connect the separating members to the strip for individual turning in opposite directions upon themselves.

110 4. In a sorting device, a strip having loops struck from the body thereof providing parallel rows of bearing sleeves, a plurality of separating members, substantially U-shaped 115 clips secured to corresponding end portions of the separating members, said separating members having notches formed in said corresponding end portions, and connecting elements having end portions bent to provide trunnions for engagement in the bearing sleeves, said elements having bight portions connected to the separating members through the medium of said clips and said bight portions having projections formed thereon for engagement in said notches and cooperating with the clips to provide substantially rigid connection between said elements and said separating members.

120 5. In a sorting device, a strip having loops struck from the body thereof providing par-

- allel rows of bearing sleeves, a plurality of separating members, substantially U-shaped clips secured to corresponding end portions of the separating members, said separating members having notches formed in said corresponding end portions, and connecting elements having end portions bent to provide trunnions for detachable engagement in the bearing sleeves, said elements having bight portions connected to the separating members through the medium of said clips and said bight portions having projections formed thereon for engagement in said notches and cooperating with the clips to provide substantially rigid connection between said elements and said separating members, and a base member supporting said strip. 30

6. In a sorting device, a strip having loops struck from the body thereof providing parallel rows of bearing sleeves, a plurality of separating members, substantially U-shaped clips secured to corresponding end portions of the separating members, said separating members having notches formed in said corresponding end portions, and connecting elements having end portions bent to provide trunnions for engagement in the bearing sleeves, said elements having bight portions connected to the separating members through the medium of said clips and said bight portions having projections formed thereon for engagement in said notches and cooperating with the clips to provide substantially rigid connection between said elements and said separating members, and a base member supporting said strip. 30
7. In a sorting device, a strip having loops struck from the body thereof providing parallel rows of bearing sleeves, a plurality of separating members, substantially U-shaped clips secured to corresponding end portions of the separating members, said separating members having notches formed in said corresponding end portions, and connecting elements having end portions bent to provide trunnions for detachable engagement in the bearing sleeves, said elements having bight portions connected to the separating members through the medium of said clips and said bight portions having projections formed thereon for engagement in said notches and cooperating with the clips to provide substantially rigid connection between said elements and said separating members, and a base member supporting said strip. 40
